UNITED STATES PATENT OFFICE.

WARD GRUNER, OF COLDWATER, MICHIGAN.

ROAD-SCRAPER.

1,088,414.

Specification of Letters Patent.

Patented Feb. 24, 1914.

Application filed August 28, 1912. Serial No. 717,644.

To all whom it may concern:

Be it known that I, WARD GRUNER, a citizen of the United States, residing at Coldwater, in the county of Branch and State of Michigan, have invented a new and useful Road-Scraper, of which the following is a specification.

This invention relates to road graders or scrapers, its principal object being to provide a machine of this character having a curved or arcuate scraping blade which is reversible and has its end portions diverging forwardly so that, as the device is drawn over a road, said forwardly diverging portions will operate as scraping and deflecting wings for gathering the loose material inwardly toward the center of the blade.

Another object is to provide a device of this character having a platform thereon for supporting the driver, it being possible for the driver to control the operation of the machine by changing his position on the platform.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a plan view of the machine. Fig. 2 is a side elevation thereof. Fig. 3 is an enlarged vertical transverse section through a portion of the blade and showing the means employed for attaching the platform to the blade.

Referring to the figures by characters of reference 1 designates a scraping blade formed of a heavy elongated sheet of metal curved so as to form forwardly diverging side wings 2 and an intermediate or rear crown portion 3. Mounted on the front and back portions of the wings 2 are front and

rear cross strips 4 and 5 respectively, supporting a platform 6 which is mounted on the middle portions of the strips. Extending downwardly through the end portions of the strips 4 and 5 are coupling bolts 7 the lower ends of which are bent at right angles as shown at 8, so as to extend through openings 9 formed in the wings 2 along the center thereof. The bolts 7 are provided with suitable means, such as nuts 10, for binding the strips 4 and 5 upon the upper edges of the wings 2.

Draft devices, such as chains 11, rods or the like, may be connected to the end portions of the front strip 4, these draft devices converging forwardly and being connected to a whiffletree 12.

In using the scraper herein described, the same is drawn forward and the forwardly diverging wings 2 will obviously gather the loosened dirt inwardly toward the center of the scraper where it will be collected after which, by raising the rear portion of the scraper, the collected material can be left in a pile upon the road. Increased pressure can be brought onto the surface of the road by subjecting the platform 6 to the weight of the driver. The driver may shift his weight toward the front end of the platform and cause the front ends of the wings 2 to dig into the soil while the intermediate or crown portion of the blade will thus be relieved of a considerable portion of the weight. Obviously, the dirt gathered up by the wings, will be directed inwardly toward the crown portion and said crown portion will ride easily over it should the dirt be gathered into depressions in the road. By shifting the weight of the driver to the back end of the platform, the intermediate or crown portion 3 of the scraper will dig into the soil with greater force than will the front ends of the wings 2 and the tendency of the scraper is thus to cut off any upwardly projecting portions of the road.

Should the lower edge of the blade 1 become unduly worn, the bolts 11 can be detached from the cross strips 4 and 5, the blade 1 reversed so as to bring its worn edge uppermost, and the bolts 7 swung within the openings 9 so as to cause them to pro-

ject above the worn edges where they can again be placed in engagement with the strips 4 and 5.

What is claimed is:—

- 5 The combination with an invertible scraping blade and a platform, of L-shaped bolts secured within the blade along the longitudinal center thereof and adjustable angularly about their points of connection, for

engaging the platform to hold it upon either 10 longitudinal edge of the blade.

In testimony that I claim the foregoing as my own, I have hereto affixed my signature in the presence of two witnesses.

WARD GRUNER.
